CLAIM

The ornamental designs for a “virtual reality headset”, as shown and described.

DESCRIPTION

FIG. 1 is a first perspective view of a virtual reality headset; FIG. 2 is a second perspective view thereof; FIG. 3 is a front view thereof; FIG. 4 is a rear view thereof; FIG. 5 is a left side view thereof; FIG. 6 is a right side view thereof; FIG. 7 is a top view thereof; and, FIG. 8 is a bottom view thereof.

The design which is claimed is shown in solid lines in the drawings. The broken lines in the figures depict portions of the virtual reality headset that form no part of the claimed design.
